Primary Examiner — Mitchell I. Siegel(74) Attorney, Agent, or Firm — Emerson Thomson
Bennett, LLC(57) CLAIM

The ornamental design for a crossbow case, as shown and described.

DESCRIPTION

FIG. 1 is a perspective view of a crossbow case.
 FIG. 2 is a top view of the crossbow case shown in FIG. 1.
 FIG. 3 is a right side view of the crossbow case shown in FIG. 1.

The broken lines illustrate the environment in which the article embodying the design may be used and form no part of the claimed design.

1 Claim, 3 Drawing SheetsFIG. 2
